UNITED STATES PATENT OFFICE.

FRANK M. HILGERINK, OF CHICAGO, ILLINOIS.

SPRAY CLEANING SYSTEM.

Application filed December 30, 1920. Serial No. 432,033.

To all whom it may concern:

Be it known that I, FRANK M. HILGERINK, a citizen of the United States, residing at Chicago, in the county of Cook and State of Illinois, have invented certain new and useful Improvements in Spray Cleaning Systems, of which the following is a specification.

This invention relates to a system for washing off the exterior surfaces of locomotives or other apparatus where grease and dust accumulate, and proceeds upon the principle of forcibly spraying against the surface to be cleaned hot water bearing a suitable content of finely subdivided cleaning oil, which is delivered against the surface to be cleaned under conditions which permit the oil to act upon the accumulated grease and foreign matter, reducing these to a condition which permits it to be readily borne off by the water as a vehicle; the mixture of oil and water being preferably acted upon by a subdividing and energizing blast of air as it issues from the nozzle, as is more fully described in the patent to Durham, et al., No. 1,113,967, Oct. 20, 1914.

One of the difficulties experienced in systems of this kind has existed in the matter of controlling the temperature of the water, keeping it above a temperature at which it ceases to become effective in removing the greasy deposit, and below an upper limit at which it becomes injurious to painted or other surfaces against which it is sprayed; and one feature of the present invention consists in providing in such a cleaning system a water heater comprising two concentric pipes, to one of which, preferably the inner one, steam is supplied under comparatively high pressure and to the other of which, preferably the outer one, or to the annular space between the pipes, is supplied water to be heated; the steam and water being fed in at opposite ends so that the water encounters the hottest part of the steam as it leaves the heater; and the steam pipe being provided with a suitable trap that permits escape of its water of precipitation without passing any of the steam. For convenience and economy of space the concentric pipes are divided into connected sections, and these sections are arranged in groups, but the effect is that of two long concentric pipes receiving the respective elements named, in the manner described.

A thermostat at the discharge end of the

water pipe, and therefore responsive to the ultimate effect of the heater, controls the valve that supplies the steam to the steam pipe, and by varying pressure of the steam, and consequently its temperature within the heater, the heating capacity is kept between the limits desired so that the water issues from the discharge end at the desired temperature, say, between 120° and 140° F. even though the water flows to the full capacity required to supply a plurality of cleaning mixture outlets in the system, and remains between said limits of temperature even though the water be shut off altogether.

Another difficulty that has been experienced in cleaning systems of this kind has occurred in connection with the feed of oil and the regulation of the proportion of oil to hot water. Another feature of the present invention consists in supplying the oil constituent of the spray from a tank and through a plurality of outlets of varying capacity, so that instead of attempting to regulate the degree of opening of a single valve according to the quantity of oil required, one or more valves of predetermined capacity, adapted either singly or collectively to supply the exact quantity, are employed. Moreover, the oil is expelled from its reservoir under pressure developed by supplying water to the bottom of the oil reservoir, preferably under the same head of pressure as that which delivers the hot water supply so that the oil as well as the hot water will be responsive to the load on the distributing line or quantity of mixture consumed, and the oil will be delivered in the same ratio to water consumption regardless of the quantities used.

In order that the invention will be fully understood, an illustrative embodiment thereof will now be described in detail in connection with the accompanying drawings.

In said drawings—

Figure 1 is a side elevation of the air, water, and oil supply apparatus together with the water heating apparatus.

Figure 2 is a plan view of the same.

Figure 3 is an end elevation of the heater.

Figure 4 is a view of the oil supply and the distributing system beyond the same; and

Figure 5 is a detail view of the spray nozzle.

1 is an air tank adapted to contain air

under pressure and supply it to the system through a pipe 2. 3 represents a steam pipe, and 4 a pipe for supplying water under a head of pressure sufficient to deliver it 5 through the system.

5 represents a heating coil which may assume any convenient form dictated by the conditions under which it is to be located, and which comprises an inner pipe 6 connected indirectly through thermostatic pressure control with the steam pipe 3 and surrounding pipe 7 which is kept supplied with water through pipe 4.

The steam pipe 6 emerges from that end 15 of the heater 5 which is opposite the end at which the heater delivers hot water, and said steam pipe enters a trap 8 of known construction which permits escape of water of condensation while confining the steam.

20 Interposed in the steam pipe 3 as it approaches the heater 5 is an automatic pressure valve 9 controlled by a thermostatic device 10 which is subject to temperature effect of water in the pipe 11 through which 25 the water escapes from the heater; the arrangement being such that the valve 9 is opened or closed as the temperature of the water in pipe 11 falls below 120° or above 140° F. A thermometer 12 may also be 30 introduced in the pipe 11 for convenience in observing the work of the heater. 13 represents a gauge through means of which to observe the working conditions on the air line 2.

35 14 is the oil tank having a suitable filling connection 15, a plurality of discharge channel 16, 16^a, and 16^b of different capacities controlled by valves 17, 17^a, and 17^b, and having a connection 11^a through which it 40 receives hot water at bottom as a means of forcing out the oil at the top; also suitable drainage outlet 18 controlled by valve 18^a through which the oil-displacing water may be discharged when it becomes necessary to 45 replenish oil in the tank, at which times the water supply will be cut off by the valve 19 and the refilling connection 15 and drainage valve 18^a opened until the tank 14 is 50 emptied of water, when valve 18^a will be closed, tank 14 will be refilled with oil through connection 15, said connection 15 will then be closed, and the water supply connection 19 will be opened to put the oil tank under delivery pressure. At such times 55 of oil replenishment in tank 14, discharge pipe 20 for the mixture of oil and water may also be closed through valve 21, thereby avoiding the necessity of changing adjustment of the proportioning valves 17, 17^a, and 17^b.

60 By having a plurality of discharge passages gauged to supply, each, a predetermined unit of an aggregate supply of oil into the stream of vehicle water, together 65 with means for independently controlling

each passage at will, it becomes an easy matter to determine with accuracy the proportion of cleansing element introduced into the water, and to accomplish this through instruction of relatively unskilled labor 70 rather than by skill of an operator; and particularly is this true when all of the discharges lead from a common supply tank to which the vehicular water is delivered under pressure, and all of the discharge passages 75 are consequently under identical discharge pressure.

By having the discharge channels 16, 16^a, and 16^b gauged to their different capacities, seven different proportions of oil may be 80 delivered to the water; that is to say, three different proportions may be delivered by simply selecting the first, second or third outlet, another proportion by opening all of the three together, and three more proportions by opening, jointly, either the first and second, or the first and third, or the second and third; and since the outlets all deliver under the same head of pressure the 85 proportioning will be accurate, and can be 90 carried out, under instruction, by unskilled labor by simply opening specified outlets to their full capacity.

Oil from the tank 14 meets hot water through branch 11^b in the mixer 20^a, whence 95 the water with its properly proportioned content of oil flows into the pipe 20, past the valve 21 to the distributing main 23. Air pipe 2 continues to the distributing points, so that at each washing station 100 there will be an outlet plug 24^a, 24^b, 24^c, etc., as well as an air outlet 2^a, 2^b, 2^c, etc. In order that each outlet 24^a, etc., may receive the proper supply of mixture when two or more stations may be in operation at the 105 same time, the distributing main 23 has its capacity reduced beyond each washing station so that it consists of a series of sections 23^a, 23^b, etc., of progressively smaller capacity.

110 In order to deliver the cleaning mixture against the locomotive or other surfaces to be cleaned, a delivery nozzle such as shown in Figure 5 is preferably used, and which comprises the conduit 25 adapted to be connected by hose 25^a to any one of the mixture plugs 24^a, etc., and an air conduit 26 having a hose 26^a through which it may receive air supply from any one of the air outlets 2^a, etc. Regulating valves 25^b and 26^b are provided on the nozzle for regulating, respectively, the supply of oil and water mixture and the supply of air. 27 represents a grip or handle through which the nozzle may be manipulated. The outlet end of the nozzle 28 is of known construction and is such that the air discharges against the mixture of oil and water after the manner of an atomizer, thus insuring a very fine subdivision and mixture of the oil and water 120 125 130

as well as lending impetus to the spray and greater effectiveness in its impingement against the surfaces to be cleaned.

From the foregoing description it will be seen that the hot water pipe constitutes a conduit for delivery of a fluid vehicle, whereas the oil tank constitutes a container for delivering, or adapted to deliver, a cleaning element into the fluid vehicle. It will also be seen that the heater insures the temperature of the fluid vehicle at a degree that conditions the cleaning element when delivered into the fluid vehicle; and that the use of the water supply and the head under which it is supplied to displace the oil from the tank is under conditions that maintains substantially identical discharge pressure through one or any number of the oil discharge passages which may be opened, so that the gauging of the oil passage becomes an accurate measure of the quantity of oil delivered.

I claim:

1. In a cleaning system, a pipe for delivering a fluid vehicle, a cleansing element supply having a plurality of differently gauged individually and collectively operable discharge passages through which it is adapted to deliver cleansing element to said pipe, and means for controlling the discharge of cleansing element through said passages, at will. 25
2. In a cleaning system, a fluid vehicle pipe, a cleansing element container, a plurality of discharge passages through each 35 and all of which said container is adapted to deliver cleansing element to said pipe, and means for opening any number of said passages at will; said passages being gauged when fully opened to predetermined diverse 40 capacity.

Signed at Chicago, Illinois, this 17th day of December, 1920.

FRANK M. HILGERINK.
